UNITED STATES PATENT OFFICE.

STEPHEN HARVEY ASSITER, OF FLOYDADA, TEXAS.

COTTON-CLEANING MACHINE.

Application filed December 22, 1926. Serial No. 156,490.

The present invention relates to improvements in cotton machinery and has for its primary object to provide a machine which will remove the shale and portions of burr or boll from the cotton which is frequently left in the cotton when the same is passed through the boll extractor.

A further object of the invention is the provision of a cotton cleaning machine particularly designed for treating what is commonly termed, "bolley" cotton to produce a higher grade of product.

A still further object of the invention is the provision of an auxiliary cotton cleaning machine which is designed to be disposed between the conventional type of boll extractor and the "gin" stand.

Still another object of the invention is the provision of an auxiliary cotton cleaning machine which is comparatively simple and of durable construction and which will be efficient in operation.

Another object of the invention is the provision of a machine of the above type which can be conveniently operated and which can be manufactured at a relatively low cost.

Other objects and advantages of the invention will become apparent as the description progresses.

In the accompanying drawings forming a part of this specification and in which like reference characters are employed to designate corresponding parts throughout the same:

Figure 1 is an end elevational view of an assembled machine constructed in accordance with my invention.

Figure 2 is a rear elevational view of the same,

Figure 3 is a front elevational view of the same,

Figure 4 is a vertical transverse sectional view taken on the center line of the machine on an enlarged scale, and

Figure 5 is a vertical longitudinal sectional view on the line 5—5 of Fig. 1.

Referring to the drawing, wherein for the purpose of illustration is shown the preferred embodiment of my invention, the numeral 10 generally designates the machine housing which is of elongated formation and polygonal in cross section. This housing embodies a pair of end walls 11 of generally rectangular formation having the corners formed at an angular inclination as will be presently indicated. Rigidly secured be-

tween the end walls 11 and extending longitudinally in the lower central portion of the housing is a trough 12, one end of which communicates with an opening 13 in one of the end walls 11.

A pair of longitudinally extending parallel brace beams 14 extend at each side of the trough 12 and are rigidly secured to the end walls. Rigidly secured on the upper horizontal edges of the end walls 11 is a longitudinal top wall 15 arranged in a horizontal position. A vertical wall 16 is rigidly secured to the upper forward portions of the end walls as shown in Figures 1 and 4. The rear side of the housing is closed by a rear wall 17 secured to the end walls and extending at an angle of inclination, the lower edge of the rear wall 17 connecting with a longitudinal rear beam 18.

Extending longitudinally at the forward side of the housing and arranged at an angle of inclination and spaced with respect to the lower edge of the wall 16 is a beam 19 to form a longitudinal intake opening. A similar beam 20 is secured at the rear side of the housing immediately below the beam 18, this beam 20 being disposed at an angle of inclination and in spaced relation to the beam 18 to form a discharge opening.

The lower portion of the housing is closed by means of metallic plates 21 and 22, the plate 21 being bent to arcuate form and secured to the forward beam 19 and the upper forward edge of the trough 12. The complementary metallic plate 22 is also bent to arcuate form and has its upper edge secured to the beam 20 and its lower edge secured to the upper rear side of the trough 12.

Journalized in openings formed in the end walls 11 and extended longitudinally through the housing is a drum shaft 23, a drive pulley 24 being rigidly secured upon one outwardly projecting end of the shaft while a sprocket wheel 25 is secured upon the opposite outwardly projecting end.

Rigidly secured upon the inner portion of the shaft 23 and rotatable therewith is a cylindrical drum 26 embodying circular heads 27 having aligned openings formed at the center for reception of the shaft 23. Rigidly fixed in the cylindrical wall of the drum and extending radially outward therefrom are a plurality of teeth 28 arranged in longitudinal rows on the wall of the drum. A baffle plate 29 is secured in horizontal position in the rear wall of the housing, this

plate being adapted to prevent the cotton being carried into the upper portion of the housing.

Secured in position immediately below the under side of the drum and spaced from the teeth thereof is a foraminous screen 30 substantially semi-circular in cross section. The forward edge of the screen 30 is secured to the beam 19 while the rear edge is attached to the inner edge of the beam 20. From this construction it is apparent that the screen 30 is disposed between the drum and the arcuate bottom plates 21 and 22.

Rotatably mounted in the trough 12 is a longitudinal spiral conveyor 31. The ends of the conveyor 31 are formed with spindles 32, one end of the conveyor being rotatably supported in a bearing opening formed in one of the end walls 11 while the opposite end projects through the opening 13 formed in the respective end wall and is rotatably supported in a bearing bracket 33 mounted on said wall.

In operation, my improved cotton cleaning machine is disposed adjacent a boll extractor and arranged so that the discharge of the extractor will be positioned against the intake opening of the machine. The auxiliary cleaning machine is arranged on a level with the top of the gin stand a little to the rear of the same so that the discharge opening of the cleaning machine is arranged in registration with the intake of the gin stand. As the cotton passes through the boll extractor, which may be of the type known as the Mitchel boll extractor, the bolls are removed but foreign matter such as shale remains mixed with the cotton. Ordinarily, this foreign matter is fed into the gin stand so that a comparatively low grade of cotton is produced. When employing the auxiliary cotton cleaning machine described in the foregoing, the particles of shale and other foreign matter are thoroughly separated from the cotton, by agitating the cotton between the rotary toothed drum and the foraminous screen 30.

As the foreign matter is separated from the cotton, it is forced through the foraminous screen and discharged into the trough 12. The particles of shale are then conveyed longitudinally through the trough and discharged into a suitable receptacle.

The machine is driven by means of a belt trained about the drive pulley 24 which will rotate the shaft 23 and drum. As clearly indicated in the drawings, a sprocket wheel 34 is rigidly secured to the projecting end of the conveyor shaft 32, this wheel being arranged in a vertical plane with the sprocket 25 secured to the drum shaft 23 and driven by means of the chain 35 trained over the sprockets. From this construction it will be noted that the conveyor is continuously rotated during the rotary movement of the

drum so that the matter separated from the cotton will be conveyed from the housing to a receptacle. Attention is also invited to the fact that the longitudinal beam 29 extends from the rear wall of the housing to a position adjacent the drum so as to obviate the possibility of cotton being carried into the upper portion of the housing and causing the same to be discharged through the rear opening.

Thus, it is apparent, that a comparatively simple machine has been produced which may be conveniently connected between a conventional type of boll extractor and gin stand to effectively remove extraneous matter from the cotton so as to produce a relatively higher standard of product.

It is to be understood that the form of my invention herewith shown and described is to be taken as the preferred example of the same, and that various changes as to the shape, size and arrangement of parts may be resorted to without departing from the spirit of the invention or the scope of the subjoined claim.

Having thus described my invention, I claim:

In a cotton cleaning machine, an elongated hollow body comprising a top wall, a relatively shallow front wall depending from the forward side of the top wall, and a downwardly and rearwardly inclined rear wall extending from the rear side of the front wall, a relatively shallow vertical wall section extending longitudinally at the lower edge of the said inclined rear wall, an upwardly and forwardly inclined beam, the body of the cleaner further including end walls, the said beam extending between the ends walls in spaced relation to and in a plane below the lower edge of the front wall, a rearwardly and downwardly inclined member extending between the end walls and in a plane below and spaced with respect to the lower edge of the vertical rear wall section, a drum rotatably mounted in the body and having its circumference located relatively close to the lower edge of the front wall and the lower edge of the said beam, the said surface of the drum being located relatively close to the upper forward edge of the member which extends below and in spaced relation to the lower edge of the vertical rear wall section, a baffle extending longitudinally between the end walls of the body and forwardly within the body from substantially the upper edge of the said vertical rear wall section with its forward edge located relatively close to the circumference of the said drum, teeth upon the surface of the drum, a foraminous screen secured at its forward and rear edges respectively to the forward beam which is located below and in spaced relation to the front wall of the body and to the forward

and upper edge of the member which is located below and in spaced relation to the vertical rear wall section, the said screen being curved concentric to the said drum,
5 a trough extending longitudinally beneath the drum substantially in the vertical plane of the axis of rotation of the drum, imperforate bottom members extending on curved lines between the said beam at the
10 front of the body and the forward upper

side of the trough and between the upper rear side of the trough and the said member which extends below and in spaced relation to the vertical rear wall section, a screw conveyor operating in said trough, and 15 means for imparting rotary motion simultaneously to the said drum and to the said conveyor.

In testimony whereof I affix my signature.
STEPHEN HARVEY ASSITER.
